DESIGN FOR AN ELECTRIC BROILER

Frederick Conrad Kimmel, Rochester, N. Y.

Application March 3, 1938, Serial No. 75,565

Term of patent 14 years

To all whom it may concern:

Be it known that I, Frederick Conrad Kimmel, a citizen of the United States, residing at 28 Riverside Street, in the city of Rochester, and in the county of Monroe and State of New York, have invented a new, original, and ornamental Design for an Electric Broiler, of which the following is a specification, reference being had to the accompanying drawing, forming part thereof, wherein

Fig. 1 is a side elevational view of an electric broiler showing my new design.

Fig. 2 is a top view of the electric broiler shown in Fig. 1.

I claim:

The ornamental design for an electric broiler, as shown.

FREDERICK CONRAD KIMMEL.
